MULTI-OUTLET ELECTRIC EXTENSION CORD
Eugene G. Danner, 9122 71st Road, Forest Hills, N.Y.

Filed Nov. 14, 1963, Ser. No. 77,421
Term of patent 14 years
(Cl. D26—1)

FIG. 6

FIG. 7

FIG. 1 is a perspective view of the multi-outlet electric extension cord, showing my new design;

FIG. 2 is a front view thereof;

FIG. 3 is a side view thereof;

FIG. 4 is a top view thereof;

FIG. 5 is a bottom view thereof;

FIG. 6 is a rear view thereof, and

FIG. 7 is a side view, opposite to the side view shown in FIG. 3.

A portion of the line cord has been broken away for convenience of illustration.

I claim:

The ornamental design for a multi-outlet electric extension cord, as shown and described.
